UNITED STATES PATENT OFFICE.

ARTHUR R. KRAUSE, OF WOODHAVEN, NEW YORK, ASSIGNOR TO THE LION ELECTRIC MANUFACTURING CO., INC., A CORPORATION OF NEW YORK.

DESIGN FOR A LIGHTING FIXTURE.

Application filed February 23, 1926. Serial No. 16,634. Term of patent 7 years.

To all whom it may concern:

Be it known that I, ARTHUR R. KRAUSE, a citizen of the United States, and a resident of Woodhaven, county of Queens, and State of New York, have invented a new, original, and ornamental Design for Lighting Fixtures, of which the following is a specification, reference being had to the accompanying drawing, forming a part thereof.

In these drawings:

Figure 1 is a front elevational view of the lighting fixture, the part shown in full line outline being ornamented in the same manner as the part more fully illustrated; and

Figure 2 is a diagrammatic top plan view of the lighting fixture.

I claim:

The ornamental design for a lighting fixture, substantially as shown and described.

ARTHUR R. KRAUSE.
